United States Patent Office

Des. 203,677
Patented Feb. 8, 1966

203,677

SET OF HEADPHONES

Raymond Spilman, Darien, Conn., and Charles F. Stephenson, New York, and Morton Gerard, Brooklyn, N.Y., assignors to The Astatic Corporation, Conneaut, Ohio, a corporation of Ohio

Filed July 30, 1963, Ser. No. 76,042

Term of patent 7 years

(Cl. D26—14)

FIG. 1

FIG. 2

FIG. 3

FIG. 1 is a fragmentary perspective view of a set of headphones, showing our new design;

FIG. 2 is a perspective view, to an enlarged scale, with an earphone in another position; and

FIG. 3 is a perspective view of one of the earphones thereof, to an enlarged scale.

We claim:

The ornamental design for a set of headphones, as shown.
